UNITED STATES PATENT OFFICE.

THOMAS G. HAWKES, OF CORNING, NEW YORK.

DESIGN FOR THE ORNAMENTATION OF GLASSWARE.

SPECIFICATION forming part of Design No. 19,865, dated June 3, 1890.

Application filed May 5, 1890. Serial No. 350,700. Term of patent 14 years.

To all whom it may concern:

Be it known that I, THOMAS G. HAWKES, a citizen of the United States, residing at Corning, in the county of Steuben and State of New York, have invented and produced a new and original Design for the Ornamentation of Glass and other Ware, of which the following is a specification, reference being had to the accompanying drawings, forming part thereof, in which—

Figure I is a side elevation of a glass bowl showing my design. Fig. II is a bottom view thereof.

The leading features of my design consist in a large center star having elongated radiating ovate figures alternating with shorter fan-shaped figures, large fan figures extending outward from the ovate figures, and star

figures in the spaces between the ovate figures and the large fan figures, having rosettes 20 at the corners of the spaces.

1 are the ovate figures, 2 the alternate fan figures, 3 the large fan figures, 4 the star figures, and 5 the rosettes in the corners of the spaces between the outer ends of the 25 ovate figures and the large fan figures.

Having thus described my invention, the following is what I claim as new therein and desire to secure by Design Letters Patent:

The design for the ornamentation of glass 30 and other ware, substantially as herein shown and described.

THOMAS G. HAWKES.
